UNITED STATES PATENT OFFICE

116,230

DESIGN FOR A TOY

John W. Gibson, Kansas City, Mo., assignor, by direct and mesne assignments, to Jesse V.
Kelly, Kansas City, Mo.

Application May 22, 1939, Serial No. 85,114

Term of patent 7 years

To all whom it may concern:

Be it known that I, John W. Gibson, a citizen of the United States, residing at Kansas City, in the county of Jackson and State of Missouri, have invented a new, original, and ornamental Design for a Toy of which the following is a specification, reference being had to the accompanying drawing, forming a part thereof.

Fig. 1 is a plan view of the toy showing my new design.

Fig. 2 is a side elevational view thereof.

Fig. 3 is a front elevational view thereof.

I claim:

The ornamental design for a toy, as shown.

JOHN W. GIBSON.
